[57] CLAIM

The ornamental design for a distance marker for golf course, as shown and described.

DESCRIPTION

FIG. 1 is a perspective view of a distance marker for golf course, showing my design;

FIG. 2 is a top plan thereof;

FIG. 3 is a front elevation view thereof;

FIG. 4 is a left side elevation view thereof;

FIG. 5 is a bottom plan view thereof;

FIG. 6 is a rear elevation view thereof; and,

FIG. 7 is a right side elevation view thereof.

The broken line showing of yardage is for illustrative purposes only and forms no part of the claimed design.
